UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

DRILLING APPARATUS

Application filed December 28, 1928. Serial No. 328,869.

This invention relates to fluid actuated rock drills, but more particularly to a drilling apparatus adapted to be disposed in the drill hole for drilling holes of considerable 5 depth and of large diameter.

One object of the invention is to assure a clean working surface through the use of means whereby the cuttings will be expelled from the drill hole as rapidly as 10 formed, by pressure fluid without materially increasing the pressure fluid consumption normally required for actuating the rock drill.

Other objects will be in part obvious and 15 in part pointed out hereinafter.

In the drawings illustrating one form which the invention may assume in practice,

Figure 1 is an elevation partly in section 20 of a drilling apparatus constructed in accordance with the practice of the invention, showing the apparatus disposed in the drill hole,

Figure 2 is a transverse view taken 25 through Figure 1 on the line 2—2 looking in the direction indicated by the arrows, and

Figure 3 is a view similar to Figure 1 showing a modified form of the invention.

Referring more particularly to the drawings, A designates generally a drilling apparatus and B a drill hole into which the drilling apparatus A is disposed for drilling the rock C.

The drilling apparatus illustrated is 35 adapted more particularly for open pit drilling as in ore deposits in which it is advantageous to drill holes of large diameter to receive explosive material in the form known as bag cartridges. Through the use 40 of this method the rock will merely be loosened instead of displaced so that it may be conveniently handled by the excavating machinery. It will thus be seen that this 45 method of drilling differs from the more familiar method of drilling holes of small diameter and in which only the drill steel enters the rock.

The apparatus comprises in this instance 50 a rock drill D which may be of any known

type and has a cylinder E and a front head F into which extends a drill steel G adapted to be actuated by the hammer piston (not shown) of the drill. At the rearward end of the cylinder E is a back head H which 55 may have a rearward extension J with an annular flange K at its free end to which is fixedly secured a casing L.

The casing L is preferably arranged coaxially with respect to the rock drill D and 60 may be of a diameter somewhat smaller than the drill hole B into which the casing L is disposed so that water introduced into the drill hole B from a connection O may 65 flow freely between the surfaces of the drill hole B and the casing A into the bottom of the drill hole.

In the form of the invention illustrated the back head H is provided with an inlet 70 passage P which is threaded at its outer end for connection to a pipe Q through which the pressure fluid may be introduced into the drill for actuating said drill. The pipe Q is preferably of such proportions and 75 length that it may serve as a handle for the rock drill to press it to the work and also for convenience in lowering and raising the drilling apparatus into and out of the hole B.

The drill steel G may be in all essential 80 respects substantially like the ordinary type of drill steel. As illustrated it differs therefrom only in that the cutting bit R is preferably of slightly larger diameter than any other portion of the drilling apparatus to 85 assure such clearance between the wall of the drill hole B and the casing A as may be necessary for the admission of water into the drill hole.

Heretofore difficulties which have proved 90 well nigh insurmountable have been encountered in efforts to drill holes of such diameter as to enable the entire drilling apparatus to be disposed therein. The principal difficulty was the matter of removing 95 the detritus from the drill hole, particularly in ore deposits where the elements of greater specific gravity readily precipitate to the bottom of the hole. Although the bit end R of the drill steel may readily penetrate

trate such cuttings, there invariably comes a period where the entire drilling mechanism must of necessity be removed from the drill hole to effect a proper cleansing thereof. Various methods have been suggested and tried for cleaning the drill hole under these conditions, as for instance, the disposing of a nozzle in the bottom of the drill hole and introducing water under high pressure thereinto for carrying the cuttings to the surface of the ground. Another method which has been tried is to scrape the cuttings from the drill hole. Both of these methods have serious drawbacks. In the use of the former, it is not always possible to have an available supply of water of the pressure necessary to remove the cuttings. This leaves only the use of the other alternative, namely, scraping, which however, is a slow process and not conducive to the high drilling efficiency of which an apparatus of this type is capable.

The present invention contemplates the maintenance of a clean working face by removing the cuttings from the bottom of the drill hole as rapidly as they are formed. To this end the apparatus is provided with a pipe S which is disposed in this instance within the casing A and which may project 5 with its forward or lowermost end T to a point near the corresponding end of the casing A and preferably in as close proximity to the drill bit R as is practicable.

In the end T of the pipe S is the inlet opening U which is preferably of restricted cross sectional area so that any rock particle which may enter said inlet opening will readily pass through the main body portion of the pipe S. In the accompanying illustration this is accomplished by merely flattening the end T of the pipe S.

The pipe S extends through the casing A and is threaded at its uppermost end V for engagement with threads W of a passage X in the flange K of the back head H. The passage X extends through the flange K and is provided with threads Y at its opposite end for engagement with a conduit Z which is preferably in the form of a flexible hose and extends to the surface of the ground for conveying cuttings and water issuing from the pipe S to the surface of the ground.

During drilling the cuttings will of course be constantly agitated by the drill bit R so that they will remain momentarily suspended in the water surrounding the inlet opening U of the pipe S and while the cuttings are thus suspended they should be immediately expelled from the drill hole. The means provided for this purpose comprises in this instance a conduit b the upper end of which is threaded into the exhaust port e of the cylinder E. The other or lower end of the conduit is preferably of syphonic shape and has an up-turned end d which

projects into the inlet opening U to introduce a jet of pressure fluid, in this instance, the exhaust fluid from the cylinder E, into the pipe S for drawing the cuttings into the pipe S and for elevating them through said pipe and through the conduit b to the surface of the ground.

In the drawings the lowermost end of the casing A extends to the point near the cutting bit R. This end of the casing of course 75 is open and water may therefore enter the lower end of the casing. The water however, will not rise to an elevation where it may find entrance into the rock drill for the reason that pressure fluid is constantly 80 leaking from various portions of the rock drill, particularly from the opening in the front end of the front head F into which the drill steel G extends. Such leakage pressure fluid will air-pack the drill and, 85 since the casing A is sealed at its front end by the water, the water within the casing will always remain at a low level, that is, the surface of the water will always remain considerably below the lowermost portion 90 of the rock drill.

In practice, after the drill hole B has been drilled to such a depth that the lowermost end of the casing A may extend thereinto, water may be introduced into the drill hole from the connection Q to seal the front end of the casing A and thus make it possible for the cuttings to be whirled into the vicinity of the inlet opening U of the pipe S into which they will be drawn by the exhaust fluid from the exhaust port e issuing from the end d of the conduit b. The cuttings will then be expelled through the pipe S and the conduit Z to the surface of the ground.

As the drill hole deepens the drilling apparatus will follow the progress of the drill bit R of its own weight and when this does not prove adequate for the best drilling results additional pressure may be manually applied to the pipe Q.

By means of the present invention the same favorable drilling conditions existing at the beginning of the hole will also exist at greater depths since the progress of the drill steel will at no time be impeded by the formation of a cushion of ore particles in advance of the drill bit R.

In the modification shown in Fig. 3 the apparatus is provided with a pipe e substantially similar to the pipe S in the preferred modification. In the present instance however, the pipe e is provided with a plurality of ports f at a point remote from the inlet opening T for the admission of pressure fluid into the pipe e to elevate the liquid and cuttings through the said pipe into the conduit Z.

In this modification the pressure fluid from the cylinder E is exhausted directly 120

into the casing L through which it flows to the ports f.

During the operation of this modified form of the invention the exhaust fluid flowing from the cylinder E into the casing L will tend to maintain the liquid in the casing L at a level below the rock drill. By using the exhaust fluid for this purpose instead of live pressure fluid directly from the 10 source of supply a considerable economy in the matter of pressure fluid consumption will be effected.

I claim:

1. In combination with a fluid actuated 15 rock drill having a cylinder and front and back heads, of a casing fixedly attached to the rock drill and coaxially therewith, said casing being adapted to extend into a hole being drilled to form a chamber for pressure fluid around and forwardly of the rock drill and thus prevent the admission of liquid into the rock drill, a pipe disposed between the rock drill and the casing and being fixedly connected to the rock drill, 20 25 and a conduit for introducing exhaust fluid from the cylinder into the pipe to carry cuttings and liquid therethrough from the drill hole.

2. In combination with a fluid actuated 30 rock drill having a cylinder and front and back heads, of a casing fixedly attached at one end to the back head and adapted to extend into a hole being drilled to form a chamber for pressure fluid around and forwardly of the rock drill and thus prevent the admission of liquid into the rock drill, said casing being arranged coaxially with respect to the rock drill, a pipe within the casing having a restricted inlet opening and being fixedly secured to the back head, and a conduit connected to the cylinder and extending into the restricted inlet opening of the pipe for introducing exhaust fluid from the cylinder into the pipe to carry cuttings 40 45 and liquid therethrough from the drill hole.

3. In combination with a fluid actuated rock drill having a cylinder and a front head, of a back head for the cylinder having a passage, a casing attached fixedly to the 50 back head and adapted to extend forwardly of the front head to form a chamber for pressure fluid around the rock drill and thus prevent the admission of liquid into the rock drill, a pipe threaded at one end 55 into the passage and being disposed between the rock drill and the casing, said pipe having a restricted inlet opening, a conduit for conveying exhaust fluid from the cylinder into the inlet opening of the 60 pipe to expel cuttings and liquid from a hole being drilled, and a tube threaded into the passage in the back head for conveying such cuttings and liquid from the drill hole.

4. In combination with a fluid actuated 5 rock drill having a cylinder and front and

back heads, of a casing fixedly attached to the rock drill coaxially therewith, said casing being adapted to extend into a hole being drilled to form a chamber for pressure fluid around and forwardly of the rock drill and thus prevent the admission of liquid into the rock drill, a pipe disposed between the rock drill and the casing and being fixedly connected to the rock drill, and a conduit for introducing pressure fluid into the pipe to carry cuttings and liquid therethrough from the drill hole.

5. In combination with a fluid actuated rock drill having a cylinder and front and back heads, of a casing for the rock drill having an open end disposed at a point beyond the front end of the drill, said casing being adapted to extend into a hole being drilled to form a chamber for leakage pressure fluid from the rock drill around and forwardly of the rock drill to prevent the admission of liquid into the drill, a pipe disposed between the rock drill and the casing, and means for introducing exhaust fluid from the cylinder into the pipe to carry cuttings and liquid therethrough from the drill hole.

In testimony whereof I have signed this specification.
